UNITED STATES PATENT OFFICE

DANIEL J. KELLEY, OF GREAT NECK, NEW YORK

DESIGN FOR AN AUTO-PLATE

Application filed October 10, 1932. Serial No. 45,273. Term of patent 3½ years.

To all whom it may concern:

Be it known that I, DANIEL J. KELLEY, a citizen of the United States, residing at Great Neck, in the county of Nassau and State of New York, have invented a new, original, and ornamental Design for an Auto-Plate, of which the following is a specification, reference being had to the accompanying drawing, forming part thereof.

In the drawing:

Fig. 1 is a front elevation of the auto-plate, showing my new design; and
Fig. 2 is a side elevation of the same.

I claim:

The ornamental design for an auto-plate, as shown.

DANIEL J. KELLEY.
